UNITED STATES PATENT OFFICE.

LUKE A. WILLIAMS, OF MEADVILLE, MISSOURI.

CHECK-ROWER.

SPECIFICATION forming part of Letters Patent No. 271,756, dated February 6, 1883.

Application filed June 21, 1882. (No model.)

To all whom it may concern:

Be it known that I, LUKE A. WILLIAMS, of Meadville, in the county of Linn, and State of Missouri, have invented certain new and useful Improvements in Check-Rowers; and I do hereby declare that the following is a full, clear, and exact description of the invention, which will enable others skilled in the art to which it appertains to make and use the same, reference being had to the accompanying drawings, which form a part of this specification.

Figure 1 is a front view. Fig. 2 is a rear view. Fig. 3 is a top view, and Fig. 4 is a side view.

Corresponding parts in the several figures are denoted by like letters of reference.

This invention relates to check-rowers; and it consists in certain improvements in the construction of the same, which will be hereinafter fully described, and particularly pointed out in the claim.

In the drawings hereto annexed, A represents a transverse beam, which may be one of the frame-beams of the planter of which my invention may be said to form part, but which is not shown in the drawings. The ends of beam A have cross-pieces B B, to the ends of which are riveted or otherwise secured U-shaped clips C, the outer sides of which have outward-projecting curved or nearly U-shaped brackets, D, made of spring-steel, or other elastic material. The outer sides of said brackets have inward-projecting shafts, E, on which are journaled the pulleys F, supporting a knotted rope or a wire, G, provided with buttons H, equal distances apart. On top of beam A suitable bearings are provided for a shaft, I, the ends of which project beyond the ends of said beam A, and carry sprocket-wheels J, the arms of which are slightly curved, as shown, and forked, so as to engage the knots or buttons upon the ropes or wire. Each of the sprock-

et-wheels consists of two disks or castings, J', the curved arms of which are turned slightly outward, so that when the said castings are placed together the arms shall project in opposite directions, thus forming practically single forked arms. Washers J² are placed between the disks or castings composing each sprocket-wheel, so as to spread them apart, when a rope or wire, larger than usual, is to be employed. The shaft I is provided with radially-projecting arms K, engaging a suitably-constructed cam-lever, L, pivoted upon the rear side of beam A, and connected by a rod, M, with one end of a lever, N, the other end of which is to be suitably connected to the seed-slide of the planter to which motion is thus conveyed.

The operation of my invention will be readily understood. When the machine passes over the field the rope or wire, which has been previously stretched in the usual manner, and which is supported upon the pulley F, engages the sprocket-wheels J, thus causing the shaft I to revolve intermittently, and operating the seeding mechanism.

My improved check-rower is simple, convenient, and durable, and may be constructed at a small cost.

I claim and desire to secure by Letters Patent—

The clips C, having U-shaped spring-brackets D, provided with inward-projecting shafts E, in combination with the pulleys F, as set forth.

In testimony that I claim the foregoing as my own I have hereto affixed my signature in presence of two witnesses.

LUKE A. WILLIAMS.
